GOLF CLUB HEAD CLEANING TOOL

James H. Anderson, Placerville, Calif.
(288 Brookside Ave., Ben Lomond, Calif. 95005)

Filed Oct. 4, 1966, Ser. No. 4,155

Term of patent 14 years

(Cl. D34—5)

FIGURE 1 is a side elevational view of a golf club head cleaning tool, showing my new design, the cap being removed to disclose the chisel portion of the tool, the opposite side being substantially identical in appearance;

FIGURE 2 is a front elevational view of FIGURE 1, the opposite side being substantially identical in appearance; and

FIGURE 3 is a top plan view.

I claim:

The ornamental design for a golf club head cleaning tool, as shown and described.
